UNITED STATES PATENT OFFICE.

EDWIN N. PREBLE, OF BEVERLY, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

1,149,290.

Specification of Letters Patent.

Patented Aug. 10, 1915.

Application filed October 30, 1912. Serial No. 728,584.

To all whom it may concern:

Be it known that I, EDWIN N. PREBLE, a citizen of the United States, residing at Beverly, in the county of Essex and State 5 of Massachusetts, have invented certain new and useful Improvements in Sole-Pressing Machines; and I do hereby declare the following to be a full, clear, and exact description of the invention, such as will enable 10 others skilled in the art to which it appertains to make and use the same.

The present invention relates to sole pressing machines, and more particularly to machines of this type which are employed for 15 operating upon flat soles before they have been incorporated in a boot or shoe. In machines of this type, the flat sole is first positioned upon the supporting form by a gage contacting generally with the heel end of 20 the sole, and is then clamped in position by a suitable gripping device. For various reasons, however, there is a tendency for the edge of the sole to move out of contact with the gage before it is clamped in position, disturbing the accurate positioning of the sole between the forms and reducing the 25 efficiency of the molding operation.

One object of the present invention is to 30 provide a gripping device which will force the sole against the gage when clamping the sole to the supporting form and tend to counteract any movement of the sole away from the gage. With this object in view, a 35 feature of the invention contemplates the provision in a machine of this type having a sole gage, of a gripping member and mechanism for actuating the gripping member to cause the sole engaging surface of the member to move toward the sole gage as the 40 member is moved into a clamping position. Spring heel soles are molded over the entire surface of the sole and the heel lift is applied prior to the molding operation, thus 45 causing any portion of the sole surface which is marred during the molding operation to show in the finished shoe.

A further object of the present invention is to provide a gripping device for use in 50 machines of this type having an improved construction and mode of operation in order that spring heel soles may be properly positioned and molded between the two co-operating forms without marring or injuring any portion of the sole surface. With 55 this object in view, one feature of the in-

vention contemplates the provision in a machine of this type having upper and lower forms, of a gripping device for clamping the flat sole to a supporting form and having a sole engaging surface arranged to register with a coöperating recess formed in one of the forms to present a smooth, substantially unbroken pressing surface to the sole when the forms are in a position of pressure.

Further features of the invention consist in certain novel features of construction, combinations and arrangements of parts hereinafter described and claimed, the advantages of which will be apparent to those skilled in the art from the following description.

In the accompanying drawings illustrating the preferred form of the invention; Figure 1 represents an elevation partly in section of the upper and lower pressing forms and the coöperating sole gaging and gripping mechanisms; Fig. 2 is a plan view of the construction shown in Fig. 1; and Fig. 3 is a detail illustrating the normal position of the gripping member prior to clamping the sole in position upon the supporting form.

The illustrated embodiment of the invention is shown in connection with a machine of the type described and illustrated in a co-pending application of the inventor, Serial No. 567,558, filed June 18, 1910. In this machine the sole is clamped in pressing position between a lower form 1 and an upper form 2 actuated in the usual manner by mechanism not shown. The sole is positioned upon the supporting form 1 by a heel gage 4 which is normally held in position above the surface of the form by a spring 5 and is caused to move downwardly with the heel end of the sole by the downward movement of the gripping device. The gripping device is fulcrumed at 7 and is moved into and out of engagement with the sole by a roll 8 engaging with the upper surface of the gripper arm 9 and rolling thereover as the lower form is moved horizontally to and from a position of clearance.

In spring heel soles the heel lift is attached prior to the molding operation and it is therefore very desirable to properly position and clamp the sole upon the supporting form without marring or otherwise injuring the surface of the sole. To this end,

the gripping device of the present invention is provided with a sole engaging surface registering exactly with a recess formed in the pressing form so that when the two forms are in pressing position a smooth, substantially unbroken pressing surface is presented to the work to mold the sole without marring the surface. The gripper arm 9 is provided with an upstanding projection 10 formed integral therewith which supports a forwardly extending arm 14 upon the outer end of which a gripping member 15 is carried. The arm 14 is slidingly supported upon the member 12 by coöperating ways formed upon the arm and member and the arm is clamped in any adjusted position by a clamping bolt 17 threadedly mounted in the member 12 and passing through a slot formed in the arm 14. The gripping member 15 is provided with a lug 18 formed integral therewith and received in the bifurcated outer end 16 of the arm 14, the two being pivotally connected by a bolt 19. The upper form 2 is provided with the usual slot 20 to receive the gripper arm, and in addition, a shallow recess 21 is provided in the pressing face of the form which registers exactly with the gripping member 15 so that when the two forms are in a pressure producing position the complete pressing face formed by the faces of the form 2 and gripping member 15 is a smooth, substantially unbroken surface. The gripping member 15 is a comparatively thin plate covering the entire heel portion of the sole, and having its upper edge beveled off to allow the upper form to readily pass thereover, and its lower sole engaging face conforming exactly with the recess in the form. It will be noted from an inspection of Fig. 1 that in this type of sole a sharp break is formed at the shank, which break shortens the sole and tends to draw the two ends together. In order to properly position the sole it is desirable that the gripping device shall force the heel end of the sole into contact with the gage and retain the sole in this position during the pressing operation. To this end, the sole engaging surface of the gripping member 15 is normally positioned at an angle to the sole, as shown clearly in Fig. 3 and when the gripping member is moved downwardly to clamp the sole to the form, the sole engaging surface of the member is turned into a position parallel to the surface of the sole, which turning movement causes a longitudinal movement of the sole engaging surface toward the heel gage, forcing the sole into contact with the gage. To this end, the lug 18 has a flat spring 23 attached thereto by screws 24, the spring having its upper end bent to engage with the lower surface of the arm

14 to normally retain the gripping member in the position shown in Fig. 3. When the gripping member is depressed to clamp the sole in position, the rear portion of the face first engages with the heel end of the sole and as the gripping member then forces the sole into engagement with the form, the member is moved against the force of the spring 23 to cause its entire surface to engage with the heel portion of the sole.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:—

1. A sole pressing machine, having, in combination, a pair of coöperating pressing forms, a gage for positioning the sole relative to the forms, a gripping member, and mechanism for actuating the gripping member to cause the sole engaging surface of the member to move toward the gage as the member is moved into a clamping position.

2. A sole pressing machine, having, in combination, a supporting form, a coöperating pressing form having a recess formed in the face, a plate engaging with substantially the entire heel portion of the sole and having a sole engaging surface conforming exactly with the recess in the pressing form, and mechanism for actuating the plate to clamp the sole prior to the relative movement of the forms into pressing position.

3. A sole pressing machine, having in combination, a pair of coöperating forms, a gage for positioning the sole relative to the forms, a gripping device independent of the gage and having a sole engaging surface normally positioned at an angle to the coöperating portion of the sole supporting form, and mechanism for actuating the gripping device to cause the sole engaging surface to be turned into a position parallel to the surface of the form upon a movement of the gripper into clamping position.

4. A sole pressing machine, having, in combination, a pair of coöperating forms, a gage for positioning the sole relative to the forms, an arm, a gripping member pivotally connected to the arm, and a spring normally retaining the sole engaging surface of the member at an angle to the sole with the portion of the surface adjacent to the gage nearest to the sole.

EDWIN N. PREBLE.
